UNITED STATES PATENT OFFICE.

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

ELECTRIC COUPLING DEVICE.

Application filed March 1, 1923. Serial No. 622,098.

This invention relates to an electric train line coupling of the type adapted to automatically make the electric train line circuits when cars are brought together and break said circuits when the cars are separated.

Particularly in the case of train line circuits carrying heavy currents, such as the bus line circuit, when cars are separated with the current on, excessive and damaging arcing is liable to occur.

In order to overcome the above difficulty, the principal object of my invention is to provide means for automatically opening the train line circuit in the act of uncoupling before the coupling contacts separate, so that there will be no arcing at the contacts when the contacts separate.

In the accompanying drawing; Fig. 1 is a diagrammatic view, partly in section, of electric train line couplings as applied to two cars of a train and embodying my invention, the cars being shown in the fully coupled position; and Fig. 2 a view similar to Fig. 1, showing the couplers after an initial movement in the act of uncoupling the cars.

In the drawing, the letters A and B indicate the adjacent ends of two cars, each end of the car being equipped with an automatic electric train line coupling, which, for the purposes of the present invention may be indicated by a block of insulation 1 having mounted thereon a yielding contact 2, subject to the pressure of a coil spring 3. A pair of fixed contacts 4 and 5 are also mounted in the block 1 on opposite sides of the yielding contact 2, one of which is connected to a ground wire 6 and the other to a wire 7 leading to one terminal of an electro-magnet 8.

An electric switch device is provided, comprising a casing 9, having a piston chamber 10 containing a piston 11. Said piston is provided with a stem 12 carrying a contact member 13 adapted, when the piston 11 is moved outwardly, to connect fixed contacts 14 and 15. The contact 15 is connected by a wire 16 with the yielding contact 2 and the contact 14 with a train wire 17 which may be the bus line of the system.

The magnet 8 controls double beat valves 18 and 19 by which fluid under pressure is supplied to and released from the switch that there will be no danger due to the pres-

piston 11. The fixed contacts 4 and 5 in the electric train line coupling are so positioned with respect to the yielding contacts 2 that when cars are brought together, the yielding contacts 2 will engage before the fixed contacts engage and in uncoupling, the fixed contacts will separate in advance of the separation of the yielding contacts.

In operation, when cars are in the fully coupled position, as shown in Fig. 1, the fixed contacts will be in engagement as well as the yielding contacts 2, the yielding contacts 2 being retracted, compressing the springs 3, to permit engagement of the fixed contacts 4 and 5.

Each magnet 8 being energized by current flowing through the magnet from a source of current to wire 7, fixed contact 5, the fixed contact 4 in the coupling of the adjacent car and thence through wire 6 to ground, the double beat valve 18 will be seated on the valve 19 opened, so that fluid under pressure is supplied from a source of fluid pressure supply pipe 20 past the valve 19 to piston chamber 10. The piston 11 will thus be shifted to its outer position closing the bus line circuit through the contacts 14, 13, and 15.

When the cars are separated in the act of uncoupling, the fixed contacts 4 and 5 will first separate as shown in Fig. 2, while the yielding contacts 2 still remain connected, and consequently each magnet 8 is deenergized, so that the valve 19 will seat while the valve 18 will open to vent fluid from piston chamber 10. The switch piston 11 will then be shifted by spring 21, so as to open the bus line circuit at the contacts 14 and 15 and it will now be evident that when the yielding contacts 2 separate, there will be no current flowing in the bus line circuit, and consequently there will be no arcing when the contacts separate.

By reason of the resistance of the coil of the magnet 8 in the fixed contact circuit, the current flow is reduced and consequently there will be no destructive arcing when the fixed contacts separate.

It will also be evident that with the above construction, the bus line contacts at the electric train line coupling will be deenergized when not in contact with corresponding contacts of a counterpart coupling, so that there will be no danger due to the pres-

ence of exposed live contacts when the car is in its uncoupled state.

Having now described my invention, what I claim as new and desire to secure by Letters Patent, is:—

- 5 1. The combination with an automatic electric train line coupling having an electric train line contact adapted to engage a corresponding contact of a counterpart coupling when cars are brought together, of means operated by the initial separating movement of counterpart couplings in the act of uncoupling for opening the train line circuit of said contact in advance of the separation of corresponding contacts.
- 10 2. The combination with an automatic electric train line coupling having a contact connected to an electric train line and adapted to engage a corresponding contact of a counterpart coupling when cars are brought together, of an electro-pneumatic switch device operated upon the initial separating movement of connected couplings in the act of uncoupling for opening the train line circuit of said contact.
- 15 3. The combination with an automatic electric train line coupling having a contact connected to an electric train line and adapted to engage a corresponding contact of a counterpart coupling when cars are brought together, of an auxiliary contact in said coupler, an electro-magnet in a circuit connected to said contact, a fluid pressure operated switch device for controlling the

by said magnet for controlling the fluid pressure on said switch device.

4. The combination with an electric train line coupling having a yielding contact connected to an electric train line and adapted to engage a corresponding contact of a counterpart coupling, of fixed contacts in said coupling adapted to separate from corresponding fixed contacts of a counterpart coupling in the act of uncoupling and in advance of the separation of the yielding contacts, and electrically controlled means in a circuit connected to said fixed contacts for controlling the train line circuit connected to said yielding contact.

45 5. The combination with an electric train line coupling having a yielding contact connected to an electric train line and adapted to engage a corresponding contact of a counterpart coupling, of fixed contacts in said coupling adapted to separate from corresponding fixed contacts of a counterpart coupling in the act of uncoupling and in advance of the separation of the yielding contacts, an electro-magnet in a circuit connected to said fixed contacts, a fluid pressure operated switch device for controlling the train line circuit connected to said yielding contact, and valve means operated by said electro-magnet for controlling the fluid pressure on said switch device.

50 In testimony whereof I have hereunto set my hand.

CLYDE C. FARMER.
